UNITED STATES PATENT OFFICE.

ALBERT C. RALEIGH, OF SPOKANE, WASHINGTON, ASSIGNOR TO HOWARD S. CLEMMER, OF SPOKANE, WASHINGTON.

DESIGN FOR A TOY, STATUETTE, IMAGE, OR EMBLEM.

49,547.

Specification for Design.

Patented Aug. 22, 1916.

Application filed May 23, 1916. Serial No. 99,473. Term of patent 7 years.

To all whom it may concern:

Be it known that I, ALBERT C. RALEIGH, a citizen of the United States, residing at Spokane, in the county of Spokane, State of Washington, have invented a new, original, and ornamental Design for a Toy, Statuette, Image, or Emblem, of which the following is a specification, reference being had to the accompanying drawings, forming a part thereof.

The figure is a view of a toy, illustrating my new design.

I claim:

The ornamental design for a toy, statuette, image, or emblem, substantially as shown.

ALBERT C. RALEIGH.

Witnesses:

H. E. SMITH,
B. A. HOFFINE.
